UNITED STATES PATENT OFFICE.

RALPH W. ELLIOTT, OF SAN FRANCISCO, CALIFORNIA.

PNEUMATIC PUMP.

SPECIFICATION forming part of Letters Patent No. 761,065, dated May 31, 1904.

Application filed March 14, 1904. Serial No. 197,978. (No model.)

To all whom it may concern:

Be it known that I, RALPH W. ELLIOTT, a citizen of the United States, residing at San Francisco, in the county of San Francisco and State of California, have invented certain new and useful Improvements in Pneumatic Pumps, of which the following is a specification.

My invention relates to improvements in pneumatic pumps, the object of my invention being to provide an apparatus of this character which shall be cheap and simple in construction, have very few moving parts, in which the working parts shall be readily accessible, in which the cylinder itself used in connection with such pump shall be void of such movable working parts, in which the use of flexible hose or pipe may be dispensed with, and consequently the whole apparatus will be rendered more durable and reliable than heretofore.

My invention therefore resides in the novel construction, combination, and arrangement of parts for the above ends hereinafter fully specified, and particularly pointed out in the claims.

In the accompanying drawings, Figure 1 is a side elevation, the lower part of the cylinder being broken away and the casing in which the cylinder works being shown in section, showing my improved pneumatic pump in the position in which the cylinder is filled with water. Fig. 2 is a similar view, the parts being in the position in which the cylinder is partly empty of water. Fig. 3 is an enlarged vertical section of part of the discharge-pipe and the neck of the cylinder. Fig. 4 is a horizontal section on the line A A of Fig. 3. Fig. 5 is a detail side view showing the latch.

Referring to the drawings, 1 represents the casing of a well from which water is to be pumped by means of my improved pneumatic pump.

2 represents the pipe for conveying compressed air for the purpose of elevating the water. Said compressed-air pipe 2 passes into the interior of the water-outlet pipe 3, as shown at 4, and descends in the interior of

said pipe to a point where it connects through 50 a hole 5 in the pipe with a narrow annular groove 6, cut on the outside of said pipe.

The head 7 of the cylinder 8 is formed with a neck 9, fitting closely around the water-discharge-pipe and acting as a valve-casing, as 55 will be presently shown. Said head 7 rests, in the lower position of the cylinder, upon a collar 10, secured upon the water-discharge pipe. Said water-discharge pipe extends to a point near the bottom of the cylinder 8, 60 through which bottom water enters by a large flap-valve 11, hinged on one side, as shown at 12. The neck 9 of the head of the cylinder is cast with lateral extensions or wings 13, in which are formed air-conduits 14 to conduct 65 the air from the groove 6 around the water-discharge pipe to the interior of the cylinder. When the cylinder has been let down into the water, the pressure of the water raises the flap-valve 11, enters the cylinder, filling the same. 70

It will be observed that this valve is made very large, occupying almost the entire area of the bottom of the cylinder, the object being to allow the water to enter very rapidly, so that the apparatus can operate with the 75 greatest economy of time. As soon as the cylinder is filled its buoyancy is destroyed and it drops to its lowest position, in which the air-ports 14 register with the narrow annular groove 6, formed around the water-outlet pipe. The passage is immediately open for the flow of compressed air from the compressed-air pipe through said ports 14 to the cylinder. The compressed air entering the cylinder forces the water up the water-discharge pipe 3 and through a check-valve 15 in said discharge-pipe slightly above the cylinder. The expulsion of the water from the cylinder by means of the compressed air increases the buoyancy of the cylinder, so that 80 it has a tendency to rise. It is preferred not to allow the cylinder to rise the moment that its weight would be less than that of the water displaced—or, in other words, the moment its buoyancy will permit it to rise, which would 85 take place before the cylinder was completely empty of water—but rather to oppose the rise of the cylinder until it has been completely

90
95

emptied of water. This is accomplished by providing an upwardly-pointing spring-latch 16, secured upon the upper end of the neck of the cylinder, the free end of said latch engaging a collar 17, secured upon the water-discharge pipe. Said spring-latch is arranged to be of sufficient strength to resist the upward movement of the cylinder until it has been completely emptied of water. Then the cylinder moves upward into its upper position, as shown in Fig. 2. In this position the passage of the compressed air to the cylinder is closed. The ports 14 then register with the lower portion of a wide groove 18, formed on the outside of the water-discharge pipe above the lower narrow groove 6. When so registering, the compressed air can immediately escape from the cylinder to the outer air by the ports 14 in the neck thereof and by the wide upper groove. The cylinder then again fills with water; but until it is quite filled with water the drop of the cylinder is again arrested by the engagement of the spring-latch 16 against the upper shoulder of the collar 17. As soon as the weight of the cylinder has increased sufficiently to overcome said spring-latch, which takes place when the cylinder is full of water, the cylinder again drops, and the operation is repeated. Since the collars on the water-discharge pipe and the two grooves on its outer surface extend entirely around it, it is immaterial what position around said pipe the ports in the cylinder-neck or the cylinder itself assume with reference to said water-discharge pipe. The cylinder can revolve freely around said water-discharge pipe without any change in the mode of operation.

The advantages of the above construction are as follows: By making use of the water-discharge pipe as the central core of the valve controlling the compressed air any heating of said valve is prevented, because the valve-core is always filled with circulating water. By the use of the head of the cylinder as a valve-casing the construction is much simplified and the cost is reduced to a minimum. By conducting the compressed-air pipe in the interior of the water-discharge pipe a separate connection between the compressed-air pipe and the water-cylinder is dispensed with. The whole arrangement of parts renders unnecessary the use of flexible tubing or joints. The only working part of this pump—namely, the valve—may be lubricated by the introduction of oil in the upper end of the compressed-air pipe, which by gravity passes down said pipe to its opening in the lower groove on the water-discharge pipe and is applied to the walls of the valve-casing and to that part of the water-pipe which forms the core of the valve. This permits of less friction and insures a greater certainty of action. It is also of a great advantage to be able to lubricate this

valve without raising the pump to the surface 65 of the ground, which may be a distance of one hundred feet or more. The cylinder can turn in any position on its core as an axis and the ports will always register with the grooves in the water-discharge pipe. That part of the 70 valve-casing above the ports has very little wear, because during a portion of its upward and downward movement it passes and re-passes the wide upper groove on the water-discharge pipe and at that time has no contact or 75 friction with the valve-core.

I claim—

1. In a pneumatic pump, the combination of a compressed-air pipe, a water-discharge pipe, a cylinder having a neck sliding on said water-discharge pipe, said water-discharge pipe and neck thus forming valve-operating mechanism for controlling admission of the compressed air from said pipe to the cylinder, the water-discharge pipe leading to a point near the bottom of the cylinder, and having a check-valve therein and the cylinder having an inlet-valve for the water, substantially as described. 80 85

2. In a pneumatic pump, the combination of a compressed-air pipe, a water-discharge pipe, 90 a cylinder having a neck around the water-discharge pipe and moving longitudinally with regard thereto, said cylinder having a port communicating in one position with said compressed-air pipe and in another position with 95 the outer air, the water-discharge pipe leading to a point near the bottom of the cylinder and having a check-valve and the cylinder having an inlet-valve, substantially as described. 95

3. In a pneumatic pump, the combination of a compressed-air pipe, a water-discharge pipe into the interior of which the compressed-air pipe is conducted, a cylinder having a neck surrounding said water-discharge pipe and forming a valve-casing, said neck sliding on 100 said water-discharge pipe and having a port for conducting the compressed air to the cylinder, said water-discharge pipe having formed on its surface next said neck a conduit 105 into the outer air when in one position of the cylinder and having means for connecting the compressed-air pipe with said port in the other position of the cylinder, the water-discharge pipe leading to a point near the bottom of the cylinder, and having a check-valve therein, 110 and the cylinder having an inlet-valve for the water, substantially as described. 115

4. In a pneumatic pump, the combination of a compressed-air pipe, a water-discharge pipe, a cylinder having a neck surrounding said compressed-air pipe and sliding thereover, said neck having a port for compressed air and said water-discharge pipe having two annular grooves on its outer surface, said port communicating in one position with one of said 120 grooves and in the other position with the other groove, one of said grooves also communicating with the outer air simultaneously 125

with said port, and the other groove communicating with the compressed-air pipe, substantially as described.

5. In a pneumatic pump, the combination of 5 a compressed-air pipe, a water-discharge pipe, a cylinder having a neck sliding on said water-discharge pipe, said water-discharge pipe and neck thus forming valve-operating mechanism for controlling admission of the compressed 10 air from said pipe to the cylinder, the water-discharge pipe leading to a point near the bottom of the cylinder, and having a check-valve therein and the cylinder having an inlet-valve for the water, the compressed-air pipe having 15 a collar thereon and the neck having a spring-latch engaging the lower edge of the collar in one position and the upper edge of the other position to resist the movement of the cylinder due to its change in buoyancy, substantially 20 as described.
6. In a pneumatic pump, the combination of a water-discharge pipe, a compressed-air pipe leading downward in the interior of said water-discharge pipe and communicating through 25 said pipe with an annular groove formed on the outer surface of said pipe, said pipe having a second wider groove above said lower groove, a cylinder having a neck sliding on said water-discharge pipe and having a port 30 communicating simultaneously with the atmosphere, the water-discharge pipe leading to

a point near the bottom of the cylinder, and the cylinder having an inlet-valve, substantially as described.

7. In a pneumatic pump, the combination of 35 a water-discharge pipe, a compressed-air pipe leading downward in the interior of said water-discharge pipe and communicating through said pipe with an annular groove formed on the outer surface of said pipe, said pipe having a second wider groove above said lower groove, a cylinder having a neck sliding on said water-discharge pipe and having a port communicating alternately with said grooves, the upper groove also communicating simultaneously 40 with the atmosphere, the water-discharge pipe leading to a point near the bottom of the cylinder, the cylinder having an inlet-valve, said water-discharge pipe and neck having, one a collar and the other a spring-latch, extending in the direction of said collar 45 and engaging alternately the upper and lower shoulders thereof to resist the movement of the cylinder due to a change in its buoyancy, substantially as described. 50

In witness whereof I have hereunto set my hand in the presence of two subscribing witnesses.
